US0D1007514S

(12) **United States Design Patent** (10) **Patent No.:** **US D1,007,514 S**
(45) **Date of Patent:** **** Dec. 12, 2023**

(54) **SCREEN FILM APPLICATOR**

(71) Applicant: **Shenzhen Lanhe Technologies Co., Ltd.**, Shenzhen (CN)

(72) Inventors: **Yibo Li**, Guangdong (CN); **Wei Wei**, Guangdong (CN)

(73) Assignee: **SHENZHEN LANHE TECHNOLOGIES CO., LTD.**, Shenzhen (CN)

(**) Term: **15 Years**

(21) Appl. No.: **29/877,425**

(22) Filed: **Jun. 6, 2023**

(30) **Foreign Application Priority Data**

Feb. 15, 2023 (CN) 202330052228.5

(51) **LOC (14) Cl.** **14-02**

(52) **U.S. Cl.**

USPC **D14/440**; D8/14

(57) **CLAIM**

The ornamental design for a screen film applicator, as shown and described.

DESCRIPTION

FIG. 1 is a front, left and bottom perspective view of a screen film applicator showing our new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view.

The broken lines depict portions of the screen film applicator that form no part of the claimed design.

1 Claim, 8 Drawing Sheets
